HEARING AID

Leon G. Barry, Danbury, Conn., assignor to Dictograph Products Inc., Danbury, Conn., a corporation of Delaware

Filed Oct. 14, 1965, Ser. No. 87,471

Term of patent 14 years

(Cl. D26—14)

FIG. 1

FIG. 2

FIG. 3

FIG. 4

FIGURE 1 is a top plan view of a hearing aid, showing my new design;

FIGURE 2 is a perspective view of the back, top and one side of my design;

FIGURE 3 is a perspective view of the hearing aid, taken from the opposite direction of FIGURE 2 and showing the front, top and the other side of the hearing aid; and

FIGURE 4 is a perspective view of my design, showing the back, side, and bottom thereof.

I claim:

The ornamental design for a hearing aid, substantially as shown.
